UNITED STATES PATENT OFFICE.

LESTER E. OVERTON, OF BALTIMORE, MARYLAND.

TOBACCO-SMOKING PIPE.

Application filed July 31, 1926. Serial No. 126,202.

This invention relates to improvements in tobacco smoking pipes and has for its object to provide an improved construction of pipe having a tobacco chamber; a saliva-receiving chamber and a novel arrangement of passages and valve device between the two chambers and the mouthpiece whereby to prevent saliva from draining from the mouthpiece into the tobacco chamber and ensuring the collection of such saliva in the saliva chamber.

A further object is to provide a novel construction and arrangement of chambers, passages and valve whereby the same are readily accessible for cleaning.

With these, and other objects in view, the invention is illustrated in the accompanying drawing, wherein,—

Fig. 1 shows a longitudinal sectional detail through the bowl and stem and also shows the mouthpiece in side elevation.

Fig. 2 illustrates the bowl and a portion of the stem in top view.

Fig. 3 shows the detached ferrule in side elevation.

Fig. 4 illustrates the detached valve-plate and valve on an enlarged scale, and

Fig. 5 shows a sectional detail through the valve-plate and valve,—the section being taken on the line 5—5 of Fig. 4.

Referring to the drawing the numeral 6, designates the bowl of the pipe, 7 the stem thereof and 8 the mouthpiece.

The particular shapes of these elements may be varied at will and need not be those shown in the drawing.

The bowl 6 has a partition 9 which divides the same into an upper tobacco chamber 10 and a lower saliva-chamber 11. The saliva chamber 11 is closed by a detachable cap 12 which latter has a screw-threaded connection 13 with the bottom of the bowl as shown in Fig. 1 of the drawing.

From the tobacco chamber 10, there is a passage 14, which extends longitudinally through the stem 7 and in the end of this passage I provide a tube 15, having a slightly curved end 16 as and for a purpose presently to be explained.

From the lower saliva chamber 11, I provide another passage 17 which also extends longitudinally through the stem and the rear end of this passage opens into a valve-cham-

ber 18 which I form in the rear end of the stem between the two passages 14 and 17. 55

A vent passage 19 extends down through the bowl-wall from the rim-edge 20 and opens into the lower saliva-chamber 11,—the lower end of said passage 19 preferably having a tube 21 therein whose lower end 22 60 projects into the saliva-chamber and curves laterally also for a purpose that will presently be explained.

The rear end of the stem 7 is circumferentially reduced so that a ferrule 23, may 65 have one end fitted thereon and be flush on the exterior with the stem, and the rear face of the stem has a slight circular recess 24, so as to receive a circular valve-plate 25.

This valve-plate 25 as will be seen in Figs. 70 4 and 5, is circular in form and has a perforation 26, in its upper portion and has a flap-valve 27, which covers a lower perforation 28. The weight of this valve is sufficient to keep it normally closed over the 75 valve-perforation 28.

The particular construction of this valve-plate and valve is not essential but it is essential that some form of valve be provided.

It will be noted by reference to Fig. 1, 80 of the drawing that the perforation 26 in the valve-plate is so located that the tube 15, from passage 14, may project therethrough while the valve 27 and perforation 28 are so located as to be directly at the rear of the 85 saliva-passage 17.

The ferrule 23 is recessed at its forward end to fit over the reduced rear end of the stem and also has a circular recess 29 at its rear end which is internally screw-threaded 90 so as to receive the screw-threaded nipple-end 30 of the mouthpiece 8.

Between the recessed ends, the ferrule has a central reduced passage 31 and when the ferrule is in place on the stem, this central 95 passage 31 receives the curved end 16 of the tube 15 which projects through the perforation 26 in the valve-plate.

It will also be noted that when the ferrule is in place the wall in front of the central 100 passage 31, will seat against the rear face of the valve-plate and hold the latter in place in the circular recess 24 at the rear of the stem.

When the smoker draws through the stem 105 suction will be created in the tube 15 and

passage 14 to draw the smoke from the chamber 10. This same suction will also tend to keep valve 27 closed so that there will be no suction from chamber 11, through passage 17.

10 Saliva that may flow through the stem will drip into the chamber 31 of the ferrule and will flow therefrom through valve-port 28 into the valve-chamber 18 and will run through passage 17 and collect in chamber 11.

15 In case the pipe is tilted as when placed in the pocket of the user, the tube-ends 16 and 22 will prevent saliva that may have collected in either the chamber 31 or the bowl-chamber 11, from passing into the tubes 15 or 21.

20 The tube 21 and passage 19 in the bowl wall serve as vents so as to facilitate the flow of the saliva forwardly through the passage 17 into the chamber 11 of the bowl.

25 When it is desired to clean the pipe the cap 12 may be readily removed and the mouthpiece and ferrule withdrawn from the rear of the stem, whereupon the valve-plate 25 may be removed and all of the passages and parts will then be accessible for cleaning.

30 Having described my invention, I claim,—
1. A pipe having a bowl with a partition therein to form a tobacco chamber and a saliva chamber, said pipe having a stem with one passage extending therethrough from the tobacco chamber and another passage extending therethrough from the saliva chamber, a mouthpiece at the end of the stem and

a valve interposed between the mouthpiece and the passage leading to the saliva chamber of the bowl.

2. A pipe having a bowl with a partition 40 therein to form a tobacco chamber and a saliva chamber, said bowl also having a vent passage from the saliva chamber to the exterior of the bowl above said saliva passage, and a valve interposed between the 45 mouthpiece and the passage leading to the saliva chamber of the bowl.

3. A pipe having a bowl with a partition 50 therein to form a tobacco chamber and a saliva chamber, the bowl also having a vent 55 passage from the saliva chamber to the exterior of the bowl, said vent passage being provided with a tube at the saliva chamber which projects into the latter, and a valve interposed between the mouthpiece and the 55 passage leading to the saliva chamber of the bowl.

4. A pipe having a bowl with a partition 60 therein to form a tobacco chamber at the upper side and a saliva chamber at the lower side, a stem extending from the bowl and having one passage therethrough that communicates with the tobacco chamber and another passage therethrough that communicates with the saliva chamber, a mouthpiece, 65 a plate interposed between the mouthpiece and the stem, a valve in said plate and a tube projecting from the tobacco chamber passage and extending through the said plate to the rear side thereof.

70 In testimony whereof I affix my signature.
LESTER E. OVERTON.
